(No Model.)

J. H. WAGENHURST.

ROOF DOUBLE SEAMING MACHINE.

No. 331,586.

Patented Dec. 1, 1885.

UNITED STATES PATENT OFFICE.

JOHN H. WAGENHURST, OF DEWART, PENNSYLVANIA.

ROOF DOUBLE-SEAMING MACHINE.

SPECIFICATION forming part of Letters Patent No. 331,586, dated December 1, 1885.

Application filed May 19, 1885. Serial No. 165,987. (No model.)

To all whom it may concern:

Be it known that I, JOHN H. WAGENHURST, a citizen of the United States, residing at De-
wart, in the county of Northumberland, State
5 of Pennsylvania, have invented a new and use-
ful Improvement in Roof Double-Seaming Ma-
chines, which improvement is fully set forth in
the following specification and accompanying
drawings, in which—

10 Figure 1 represents a side elevation of a
seaming-machine embodying my invention.
Fig. 2 represents a top or plan view thereof,
partly broken away. Fig. 3 represents a lon-
gitudinal vertical section in line $x x$, Fig. 2.
15 Fig. 4 represents a transverse section in line
 $y y$, Fig. 2. Fig. 5 represents a transverse sec-
tion in line $z z$, Fig. 2. Fig. 6 represents a
section of a portion in line $z' z'$, Fig. 2. The
remaining figures represent various steps of
20 forming and closing a seam.

Similar letters of reference indicate corre-
sponding parts in the several figures.

My invention consists of a roof double-seam-
ing machine having means for bending roof-
25 ing plates or sheets and closing the seam
thereof by successive operations, as will be
hereinafter set forth.

It also consists in rendering the rollers of
the machine laterally adjustable.

30 It further consists in rendering the rollers
vertically adjustable.

Referring to the drawings, A represents the
frame or bed of the machine, and B represents
35 longitudinally-extending bars whose ends are
fitted to blocks C by means of tongues and
grooves, as at D, whereby said bars may be
moved laterally in said blocks.

Bearing against the outer sides of the bars
B are springs E, the pressure whereof is ad-
40 justed by means of screws F, which are con-
nected with the side pieces of the bed A.

On the blocks B are mounted rollers G G',
H H', J J', and K K', it being noticed that
45 all of said rollers, excepting the roller J', have
vertical pivots or axes, and said roller J' has
a horizontal pivot or axis. The roller G has
a beveled shoulder, L, which overhangs the
chamfered top edge of the roller G'. The roller
50 H has a right-angled shoulder, M, which over-
hangs the right-lined top of the roller H'. The
roller J is cylindrical on its working-face, and

the roller J' is spheroidal. Both rollers K K'
are cylindrical on their working-faces and
similar in their natures. The blocks C are
fitted in vertical slots in the end pieces of the
55 frame A, and have swiveled to them screws N,
whereby said blocks, and consequently the
bars B, may be raised and lowered, it being
noticed that the bars are both vertically and
laterally adjustable, whereby the rollers may
60 be set nearer to or farther from each other in
both vertical and horizontal positions, and
thus adjusted with nicety in regard to the na-
ture of the work, the degree of pressure, &c.
The bed is provided with suitable rollers,
65 whereby the machine may be readily run on
the roof or other place where seaming is re-
quired. The lower portions of the working-
rollers are reduced in diameter, so that the
70 plates or sheets may be readily entered be-
tween each pair of rollers.

When two flanged plates or sheets are placed
together as usual for roofing or other pur-
poses, as seen in Fig. 7, and the machine is
advanced thereto, the flanges of said plates or
75 sheets have their upper ends brought between
the diagonal shoulders of the roller G and
chamfered edge of the roller G', the result of
which is the partial bending of the longer
flange of the plates or sheets, forming a lip at
80 top thereof, as seen in Fig. 8. Then the roll-
ers H H' bend said lip from its diagonal to a
right-angular form, as shown in Fig. 9, after
which the rollers J J' bend the lip over the
85 top of the short flange, as seen in Fig. 10, said
lip then being compressed by the rollers K K',
the result being a tightly-closed seam, the
same having been produced in a convenient
and easy manner and without the employment
90 of an expensive machine. Theseam as formed
may now be again run through the machine,
the rollers being properly adjusted to permit
the same, the result being a doubling of the
seam and further security of the same.

On the roller G, at the base of the shoulder
L, is a circumferential groove, L', and at the
base of the chamfered edge of the roller G' is
a circumferential bead, G², which occupies
portion of the groove L', so that when the
plate or sheet enters between the rollers G G'
100 there is a perfect break at the bend of the
same, as seen in Fig. 8.

Having thus described my invention, what I claim as new, and desire to secure by Letters Patent, is—

1. In a seaming-machine, the combination of the bars B, having tongues and carrying rollers, grooved blocks C, frame A, and means, substantially as described, for adjusting said blocks C and bars B, as and for the purpose set forth.
- 10 2. A seaming-machine composed of the frame A, provided with lateral and vertical adjustable bars B, having blocks C connected therewith, rollers G G', H H', J J', and K K', all of said parts being arranged, combined, and operated substantially as and for the purpose set forth.
- 15 3. A seaming-machine having the rollers G

G', H H', and J J', the said rollers being formed, arranged, and combined substantially as described.

20 4. In a seaming-machine, the combination of the frame A, bars B, blocks C, springs E, and screws F, substantially as and for the purpose set forth.

25 5. In a seaming-machine, the frame A, provided with screws secured to blocks C, in combination with bars B, carrying rollers and adjustably attached to the said blocks C, substantially as and for the purpose set forth.

JOHN H. WAGENHURST.
